US0D1024696S

(12) **United States Design Patent** (10) **Patent No.:** **US D1,024,696 S**
(45) **Date of Patent:** **** Apr. 30, 2024**

(54) **JUICER**

(71) Applicant: **GENICOOK PRODUCT LLC**,
Garland, TX (US)

(72) Inventors: **Jianzhong Zhang**, Handan (CN); **Zuo Yang**, Handan (CN)

(73) Assignee: **GENICOOK PRODUCT LLC**

(**) Term: **15 Years**

(21) Appl. No.: **29/839,539**

(22) Filed: **May 23, 2022**

(51) LOC (14) Cl. **07-04**

(52) U.S. Cl.

USPC **D7/665**; D7/368; D7/667

(58) **Field of Classification Search**
